Attorneys

UNITED STATES PATENT OFFICE.

JAMES LENFRED WINANS, OF TOLEDO, OHIO, ASSIGNOR TO NATIONAL SPRING AND WIRE COMPANY, OF ALBION, MICHIGAN, A CORPORATION OF MICHIGAN.

CUSHION-SEAT.

1,243,787.

Specification of Letters Patent. Patented Oct. 23, 1917.

Application filed October 11, 1915. Serial No. 55,830.

To all whom it may concern:

Be it known that I, JAMES LENFRED WINANS, a citizen of the United States of America, residing at Toledo, in the county 5 of Lucas and State of Ohio, have invented certain new and useful Improvements in Cushion-Seats, of which the following is a specification, reference being had therein to the accompanying drawings.

10 The invention relates to cushion seats and has more particular reference to the means employed for quickly attaching the skirt to the spring frame inclosed thereby. To this end the invention comprises the novel construction as hereinafter set forth.

In the drawings:

Figure 1 is a longitudinal section through a seat to which my improvements are applied;

20 Fig. 2 is a perspective view of a portion of the skirt showing the attachment of the same to the spring frame; and

Fig. 3 is an enlarged section of a portion of Fig. 1.

25 A is a cushion of any suitable construction and B is the skirt depending from said cushion, which surrounds and incloses the spring frame C. D is a metallic strip secured to the inner face of the skirt and extending along adjacent to the lower edge thereof, preferably completely around the skirt, so as to form an annular frame. This strip is provided with hooked clips E for engaging the edge bar F of the spring 30 frame, said hooks being preferably formed by integral struck-out portions of the strip. The strip is also provided along its lower edge with a bead G, which as shown is deflected outward.

40 To quickly and securely attach the strip to the skirt I preferably provide a series of hooks H, which are struck outwardly from the strip and are adapted to engage the selvage or corded lower edge I of the skirt. As originally formed, these hooks H are bent, as shown in Fig. 3, so as to receive the selvage of the skirt, and they are then secured by clenching about the cord, as indicated in dotted lines in Fig. 3. This 45 operation may be quickly performed and when all of the hooks are clenched the strip is securely attached to the skirt. The bead G being deflected outward forms a guard for protecting the selvage edge of the skirt from

wear, and it also constitutes a supporting 55 bearing for the spring frame C.

With the construction as described, the spring frame and skirt frame may be manufactured and shipped independently of the cushion and its skirt. When these parts are 60 to be assembled, the skirt frame is slipped within the skirt and the hooks H are clenched over the selvage edge I. The skirt frame may then be quickly attached to the spring frame by successively engaging the hooks E therewith. This construction also permits of at 65 any time quickly detaching the skirt without injury thereto or the necessity of detaching the same from the strip D. This facilitates the replacing of a broken spring 70 or other repairs found necessary, and permits of quickly re-assembling the parts when repairs are made.

What I claim as my invention is:—

1. The combination with a cushion and a 75 depending skirt therefor, of a spring frame inclosed by said skirt, a strip extending along the lower edge of said skirt having inwardly-extending hooks for detachably engaging said spring frame, and outwardly-extending hooks on said strip for embracing the corded edge of said skirt and adapted to be pressed into clamping engagement therewith.

2. The combination with a cushion and a 85 depending skirt therefor having a corded lower edge, of a spring frame inclosed by said skirt, a metallic strip extending along the inner face of said skirt having an outwardly-deflected bead at its lower edge, and 90 series of outwardly and inwardly extending hooks integral therewith, said outwardly-extending hooks forming clamps for engaging the edge of the skirt and said inwardly-extending hooks being adapted to 95 detachably engage said spring frame and forming a support for the latter.

3. The combination with a cushion and a depending skirt therefor having a corded lower edge, of a spring frame inclosed by 100 said skirt, a metallic strip extending around the inner face of said skirt and forming an annular frame, said strip having an outwardly-deflected bead at its lower edge, and series of outwardly and inwardly extending hooks struck therefrom, said outwardly-extending hooks forming clamps for embracing said corded edge to secure 105

the strip to the skirt, and said inwardly-extending hooks being adapted for successive engagement with said spring frame to secure the skirt and form a support for the 5 spring frame.

4. The combination with a cushion, and a depending skirt therefor, of a spring frame inclosed by said skirt, a strip extending along the lower edge of said skirt having means for engaging said spring frame 10

and a series of upwardly extending hooks struck-out from the strip for forming quick attachment clips for securing said skirt to said strip.

In testimony whereof I affix my signature in presence of two witnesses.

JAMES LENFRED WINANS.
